(57) **CLAIM**

The ornamental design of the clock radio, as shown and described.

DESCRIPTION

FIG. 1 is a perspective view of a clock radio showing our new design;

FIG. 2 is a front view of the clock radio of FIG. 1;

FIG. 3 is a rear view of the clock radio of FIG. 1;

FIG. 4 is a top view of the clock radio of FIG. 1;

FIG. 5 is a left side view of the clock radio of FIG. 1; and,

FIG. 6 is a right side view of the clock radio of FIG. 1.

The broken line showing on FIGS. 1-4 is for illustrative purposes only and forms no part of the claimed design.
